(57) **CLAIM**

The ornamental design for a battery, as shown and described.

DESCRIPTION

FIG. 1 is a front view of a battery, showing my new design; FIG. 2 is a rear view of the battery of FIG. 1; FIG. 3 is a top view of the battery of FIG. 1; FIG. 4 is a bottom view of the battery of FIG. 1; FIG. 5 is a left side view of the battery of FIG. 1; FIG. 6 is a right side view of the battery of FIG. 1; FIG. 7 is a perspective view of the battery of FIG. 1; FIG. 8 is an enlarged view of the battery taken at view 8 of FIG. 4; FIG. 9 is a front view of the battery of FIG. 1 without surface shading; FIG. 10 is a rear view of the battery of FIG. 1 without surface shading; FIG. 11 is a top view of the battery of FIG. 1 without surface shading; FIG. 12 is a bottom view of the battery of FIG. 1 without surface shading; FIG. 13 is a left side view of the battery of FIG. 1 without surface shading; FIG. 14 is a right side view of the battery of FIG. 1 without surface shading; FIG. 15 is a perspective view of the battery of FIG. 1 without surface shading; and, FIG. 16 is an enlarged view of the battery taken at view 16 of FIG. 12 without surface shading. The broken lines appearing on the right and left sides of FIG. 8 represent the boundaries of the view taken at view 8 of FIG. 4 and form no part of the claimed design. The broken lines appearing on the right and left sides of FIG. 16 represent the boundaries of the view taken at view 16 of FIG. 12 and form no part of the claimed design.

1 Claim, 8 Drawing Sheets
